UNITED STATES PATENT OFFICE

136,406

DESIGN FOR A PORTABLE AERODROME LIGHT

Harold A. Cline, Cincinnati, Ohio, assignor of
one-half to John B. Cottell, Indian Hill, Cincinnati, Ohio

Application April 22, 1943, Serial No. 110,018

Term of patent 14 years

To all whom it may concern:

Be it known that I, Harold A. Cline, a citizen of the United States, residing at Cincinnati, in the county of Hamilton and State of Ohio, have invented a new, original, and ornamental Design for a Portable Aerodrome Light, of which the following is a specification, reference being had to the accompanying drawing, forming part thereof.

Fig. 1 is a top plan view of a portable aerodrome light showing my new design.

Fig. 2 is a side elevational view thereof.

Fig. 3 is a side elevational view looking in the direction of the arrow 3 of Fig. 1.

My new design is characterized by a transparent cover for the light, a square base section with rounded corners, a flat bead at the bottom of the base, a rounded bead at the top of the base section, a top section square at the bottom part thereof with rounded corners, said top section tapering in square formation with the founded corners and converging into a true conical shape, and having a carrying bail attached to the top section all as shown.

I claim:

The ornamental design for a portable aerodrome light, as shown and described.

HAROLD A. CLINE.
